LOUNGE CHAIR

Howard V. Perno, 10325 Gridley Road,
Santa Fe Springs, Calif. 90670

Filed Nov. 27, 1970, Ser. No. 26,185

Term of patent 14 years

Int. Cl. D6—02

U.S. Cl. D6—37

FIG.1

FIG.4

FIG. 1 is a perspective view of a lounge chair showing the present design;

FIG. 2 is a front elevational view thereof;

FIG. 3 is a rear elevational view of such lounge chair; and

FIG. 4 is a side elevational view thereof, the opposite side view being a mirror image thereof.

I claim:

The ornamental design for a lounge chair, substantially as shown and described.
